(57) **CLAIM**

The ornamental design for a leaf shredder attachment and trimmer, as shown and described.

DESCRIPTION

FIG. 1 is a perspective view of a leaf shredder attachment showing the present invention.

FIG. 2 is a first-side view of a leaf shredder attachment showing the present invention.

FIG. 3 is a second-side view of a leaf shredder attachment showing the present invention.

FIG. 4 is a third-side view of a leaf shredder attachment showing the present invention.

FIG. 5 is a fourth-side view of a leaf shredder attachment showing the present invention.

FIG. 6 is a top plan view of a leaf shredder attachment showing the present invention; and,

FIG. 7 is a bottom plan view of a leaf shredder attachment showing the present invention.

The broken line showing of various surface features on the figures is included for the purpose of illustrating portions of the leaf shredder attachment and forms no part of the claimed design.
